UNITED STATES PATENT OFFICE.

CARY H. RUBLE, OF POLAND, INDIANA.

COMBINED TABLE KNIFE AND FORK.

No. 914,310.

Specification of Letters Patent.

Patented March 2, 1909.

Application filed October 28, 1908. Serial No. 459,906.

To all whom it may concern:

Be it known that I, CARY H. RUBLE, a citizen of the United States, residing at Poland, in the county of Clay and State of Indiana, have invented new and useful Improvements in a Combined Table Knife and Fork, of which the following is a specification.

This invention relates to a combined table fork and knife, and more particularly to a table fork provided with a rotary knife for cutting purposes.

The invention has for one of its objects to improve and simplify the construction of devices of this character so as to be comparatively simple and inexpensive to manufacture, easily and conveniently used, and so designed as not to be cumbersome or unattractive in appearance.

Another object of the invention is the provision of a fork having a slotted shank in which is mounted a cutting wheel whereby certain foods can be conveniently cut into pieces without needing the usual table knife so that one utensil serves the purpose of two.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one embodiment of the invention, Figure 1 is a perspective view of the combined fork and knife. Fig. 2 is a longitudinal section thereof. Fig. 3 is a transverse section on line 3—3, Fig. 2.

Similar reference characters are employed to designate corresponding parts throughout the views.

Referring to the drawing, 1 designates the handle of the fork; 2, the shank; and 3, the prongs or tines thereof. The inner or heel portion of the tines and contiguous portion of the shank are provided with a single longitudinal slot 4 for receiving a rotary disk-shaped knife 5 which is mounted on a shaft 6. The shank 2 is enlarged at 3 and provided with openings 7 through which the ends of the shank or axle extend and the

ends of the axle are riveted or formed into heads so as to prevent displacement. The disk has a hub 8 and the end faces of the hub bear against the opposed walls of the slot 4 so that the wheel cannot move laterally on the shaft or axle 7. The wheel projects considerably below the under side of the fork so that food of ordinary thickness can be completely severed by the knife 5, so that the ordinary table knife will not be required, and by locating the cutter 5 in the center line of the fork, there is little danger of the fork slipping in the hand during the cutting strokes, the strokes being made in a direction longitudinally of the fork.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having thus described the invention, what I claim is:—

1. A fork provided with a central longitudinally-extending slot adjacent the inner ends of the tines of the fork, and a rotary cutter mounted in the slot and projecting above and below the fork.

2. A fork including tines, a shank, and a handle, said shank having a longitudinally-extending slot at a point between the tines and handle, in combination with an axle extending transversely to the slot, a rotary cutter mounted on the axle, said cutter having a hub arranged with its end faces bearing against the opposed walls of the slot.

In testimony whereof I affix my signature in presence of two witnesses.

CARY H. RUBLE.

Witnesses:

OWEN REEDER,
ANNA MERCHANT.
